RECEIVER

Horst Hewel, Berlin-Lichterfelde, Germany, assignor to Telefunken Gesellschaft für Drahtlose Telegraphie m. b. H., Berlin, Germany, a corporation of Germany

Application November 11, 1937, Serial No. 173,972
In Germany November 3, 1936

8 Claims. (Cl. 178—5.8)

This invention relates to radio receivers, and in particular, to receivers adapted to receive both television and video and accompanying audio or sound signals simultaneously.

It is customary in present day practice in television transmission to accompany the picture or video signals with sound or audio signals, each of the signals being placed on separate carriers, which carriers are separated in the frequency spectrum by a fixed frequency difference, regardless of which portion of the spectrum the video and accompanying sound signals are positioned at. A suitable receiver for receiving both of these transmissions under a single manual control is described in U. S. Patent No. 1,975,056, issued September 25, 1934, to Wendel L. Carlson, and entitled "Television system." In such a receiver, a common oscillator is provided with separate audio and video channels so that simultaneously tuning the radio frequency amplifier and the oscillator affects both the audio and video channels. When the audio channel is correctly tuned to receive the audio signals, the video signals are correctly tuned to pass through the video channel.

The present invention relates to an improvement in such a type of receiver in which during the tuning process, as the frequency spectrum is being covered, the video signals are prevented from going through the audio channel, thereby preventing receiving sound effects produced by the video signals. This disturbance of course, is quite great in the ordinary receiver, but by the invention hereinafter described in detail, this deleterious feature is overcome.

At the same time the invention provides for proper tuning of the audio channel so that any distortion which might arise from mistuning of this channel is overcome. Mistuning of the audio channel in the ordinary receiver gives both distorted sound outputs and poor picture reproduction because of the fixed frequency spacing between the video and audio channels. Consequently, the invention eliminates distortion in the video channel as well as the sound channel.

It is an object, therefore, of the invention to provide a simpler tuning method for combined audio and video receivers and at the same time to provide a receiver which is free from noise during the tuning process.

A further object is to provide a combined audio and video receiver in which the video channel is blocked until the audio carrier passing through the audio channel is of a predetermined value.

Another object is to provide a receiver in which

the video channel is automatically blocked and unblocked in accordance with the tuning of the sound channel, so that proper tuning of the sound channel gives proper tuning of the video channel, and at the same time, prevents the video channel from getting through the sound channel during the tuning process.

In accordance with my invention, the detector circuit of the audio channel has a portion of its energy diverted into a cut-off control device which is also connected to one of the intermediate frequency stages of the video channel. When the detector output is below a predetermined value, the cut-off control device biases the intermediate frequency amplifier of the video channel below cut-off so that no signals can pass through the video channel. When, however, the receiver is properly tuned, the sound energy exceeds the predetermined value which actuates a relay, which may be of the electro-mechanical type or of the thermionic or gaseous discharge type, to remove the bias which cuts off the intermediate frequency amplifier of the video channel and thus permit the video frequency signals to pass through the picture reproducer. The video frequency signals are prevented from passing through the audio frequency channel by using any of the well known muter or quiet automatic volume control circuits such as are well known in the art in the audio channel. Such circuits are disclosed for example in Farnham, 1,919,160 issued July 18, 1933; Kock, 2,021,939 of November 26, 1935; and Starrett, 2,023,448 of December 10, 1935.

35 Provision is also made to operate the cut-off control device from the intermediate frequency amplifier of the audio channel in receivers where automatic volume control is provided by diverting energy from the detector to control the bias of the intermediate frequency amplifier.

Referring now to the drawings in which Fig. 1 shows in block diagram form a dual receiver embodying the invention;

Fig. 2 shows schematically the control device and its connection between the audio and video channels;

Fig. 3 shows in block diagram the connection of the control device in a dual receiver where automatic volume control is provided; and

50 Fig. 4 shows a modification of the embodiment of the invention shown in Fig. 2, in which a gaseous discharge tube is used in the control device; the invention will be described in detail.

Turning now to Fig. 1 there is shown a dual audio and video receiver comprising a radio fre-

quency amplifier 1, which amplifies the received signals and is fed to a superheterodyne detector 3, which detector is also fed from the heterodyning oscillator 5. A single control tuning means 21 serves to simultaneously determine the frequency of the oscillator 5 and the pass-band of the radio frequency amplifier 1. The output of the detector 3 is fed to an intermediate frequency amplifier 7 which is broad enough to receive both the video and audio bands of frequency. The output of this amplifier is then fed simultaneously to the audio channel comprising the intermediate frequency amplifier 9, the sound detector 11, the amplifier 13, and the loud speaker 15, and to the video channel comprising the intermediate frequency amplifier 17, the detector 19, amplifier 21, and the picture reproducing device 23. Connected between the detector 11 and the intermediate frequency amplifier is the cut-off control 25, which control normally supplies cut-off bias to the first tube of the intermediate frequency amplifier 17, but when the amplitude of the detected current exceeds a predetermined value, a relay is operated to remove this cut-off bias from the intermediate frequency amplifier 17 and permits the signals from the intermediate frequency amplifier 7 to pass through the video channel.

One form of the cut-off control which may be used is shown in Fig. 2. In this figure the intermediate frequency amplifier 9 feeds energy through capacity coupling to a diode rectifier 33. A resistor 35 and condenser 37 serve to filter the radio frequency components out of the detected output and the demodulated audio frequency is then passed on through the amplifier 13 to the loud speaker 15. Connected to the audio output of the detector is a variable resistance 39 connected in series with an electromagnetic relay 41. The variable resistance 39 is used to control the amount of current flowing through the relay to determine its operating point. The relay armature 53 is connected serially with a battery and to the cathode of the first tube 47 of the intermediate frequency amplifier 17 of the video channel. The cathode of the tube 47 is connected to ground through a parallelly connected condenser 49 and resistor 51, which serve to provide the normal operating bias for the tube 47. Normally, the armature 53 is in contact with the contact point 45 so that the battery 43 impresses positive voltage on the cathode of the tube 47. Since the other side of the battery is grounded, the grid of tube 47 is maintained at a very large negative potential sufficient to cut off plate current of the tube 47. However, as the tuning of the receiver is varied so that the audio voltage begins to rise at a predetermined value of its amplitude, the relay 41 opens removing thereby the large negative bias and permitting the tube 47 to operate with normal bias.

In Fig. 3, I have shown schematically in block diagram form the receiver which is equipped with automatic volume control and in which the cut-off control device is connected between the intermediate frequency amplifier 9 and 17. A portion of the output of the detector 11 is fed back to one or more stages of intermediate frequency amplifier 9 so that the gain of the amplifier is controlled inversely as the output of the detector. The cut-off control device is now suitably connected in the plate circuits of one of the stages in the intermediate frequency amplifier in a similar fashion to that shown in Fig. 2 and described above, so that only when the plate

current of the intermediate frequency amplifier has risen to a predetermined value is the cut-off bias supplied to the intermediate frequency amplifier removed, thereby permitting the picture signals to be fed to the picture reproducer.

In Fig. 4 I have shown a modification of the invention shown in Fig. 2. In this figure, the cut-off control device employs a gaseous discharge tube having an electrode 63 in the form of a disk and a fine wire electrode 65 perpendicular and coaxial with the disk. An auxiliary electrode 67 is positioned to one side of the electrode 65. The electrode 63 is connected to a current limiting resistor to the detector output, while the electrode 65 is connected to ground so as to place the electrode 63 and 65 across the audio output voltage. Connected serially between the auxiliary electrode 67 and the electrode 65 is a resistor 69 and a battery 71 so pulled as to put negative voltage on the auxiliary electrode 67. A connection between the electrode 67 and the resistor 69 is then brought to the grid of the first tube 47 of the intermediate frequency amplifier 17, thereby impressing upon the grid a large negative voltage to render the tube 47 blocked so that no video signals can pass through the intermediate frequency amplifier 17. As the resistor is tuned, there is an increase in the amplitude of the detected audio output and when this value exceeds a predetermined point, a glow discharge will take place between the electrode 63 and the point of the electrode 65 nearest the electrode 63. As the amplitude continues to increase, the glow discharge proceeds down the length of the electrode 65 until it reaches the electrode 67, at which point the electrode 67 is virtually short-circuited to ground, and thereby removing the cut-off bias supplied to the grid of the tube 47, so that the video signals may now be suitably amplified, detected, amplified once more, and fed to the picture reproducer.

Having described my invention, what I claim is:

1. A television receiver comprising means for receiving both video and sound signalling energy, a video channel, a sound channel, means to simultaneously tune both channels, and means connected from the sound channel to the video channel to render the video channel operative only when sound energy in the sound channel exceeds a predetermined value irrespective of the energy in the video channel.

2. A television receiver comprising means for receiving both video and sound signalling energy, a video channel, a sound channel, means to simultaneously tune both channels, and means connected from the sound channel to the video channel to render the video channel operative only when maximum sound energy flows in the sound channel irrespective of the value of video energy in the video channel.

3. The method of operating a television receiver wherein there is provided separate video and sound channels, which comprises simultaneously tuning both of said channels and only maintaining the video channel operative during time intervals in which the sound channel is properly tuned with respect to a predetermined frequency irrespective of the presence of video energy.

4. A television receiver comprising means for receiving both video and sound energy, a video channel, a sound channel, a single means for simultaneously tuning both of said channels, and electromagnetic means connected from the sound

channel to the video channel to render said video channel operative only when the sound energy in the sound channel exceeds a predetermined value irrespective of the value of video energy in the video channel.

5. A television receiver comprising means for receiving both video and sound energy, a video channel, a sound channel, single means for simultaneously tuning both of said channels, and electronic means connected from the sound channel to the video channel to render said video channel operative only when the sound energy in the sound channel exceeds a predetermined value irrespective of the value of video energy in the video channel.

6. A television receiver comprising means for receiving both video and sound signalling energy, a video channel, a sound channel, means to simultaneously tune both of said channels, an intermediate frequency amplifier in said video channel, and means to render said intermediate frequency amplifier operative only when said sound energy in said sound channel exceeds a predetermined value irrespective of the video energy in the video channel.

7. A television receiver comprising means for receiving both video and sound signalling energy, a video channel, a sound channel, means to simultaneously tune both of said channels, an intermediate frequency amplifier in said video channel, and an electromagnetic relay to render said intermediate frequency amplifier operative only when said sound energy in said sound channel exceeds a predetermined value irrespective of the video energy in the video channel, said electromagnetic relay being connected in said sound channel.

8. A television receiver comprising means for receiving both video and sound signalling energy, a video channel, a sound channel, means to simultaneously tune both of said channels, an intermediate frequency amplifier in said video channel, and an electronic relay to render said intermediate frequency amplifier operative only when said sound energy in said sound channel exceeds a predetermined value irrespective of the video energy in the video channel, said electronic relay being connected in said sound channel.
